(57) **CLAIM**

The ornamental design for an external pulse generator, as shown and described.

DESCRIPTION

FIG. 1 is a top perspective view of the external pulse generator showing our new design;

FIG. 2 is a bottom perspective view thereof;

FIG. 3 is a rear elevational view thereof;

FIG. 4 is a front elevational view thereof;

FIG. 5 is a left side view thereof;

FIG. 6 is a right side view thereof;

FIG. 7 is a top view thereof; and,

FIG. 8 is a bottom view thereof.

The broken lines immediately adjacent the shaded areas represent the bounds of the claim, while all other broken lines are directed to environment and are for illustrative purposes only; the broken lines form no part of the claimed design.
